UNITED STATES PATENT OFFICE.

STANLEY R. DE PUE, OF WASHINGTON, DISTRICT OF COLUMBIA, ASSIGNOR TO CORONA TYPEWRITER COMPANY, INC., OF GROTON, NEW YORK, A CORPORATION OF NEW YORK.

COMPACTIBLE TYPEWRITING-MACHINE.

1,356,812.

Specification of Letters Patent. Patented Oct. 26, 1920.

Application filed July 2, 1917. Serial No. 178,252.

To all whom it may concern:

Be it known that I, STANLEY R. DE PUE, a citizen of the United States of America, and a resident of the city of Washington, 5 District of Columbia, have invented certain new and useful Improvements in Compactible Typewriting-Machines, of which the following is a full and clear specification.

The object of this invention is to so construct the machine that it may be compacted for convenience in transportation and storage, as more fully hereinafter set forth.

In the drawings—

Figure 1 is a vertical longitudinal sectional view of so much of a typewriting machine as is needful to illustrate my present improvements;

Fig. 2 is a detail perspective view of the vertically movable frame adapted to carry 20 the platen carriage;

Fig. 3 is a perspective view in detail of the base frame;

Fig. 4 is a detail vertical sectional view through one of the vertical guides of the 25 base frame; and

Fig. 5 is a plan view of a portion of the machine, the platen being broken away; and

Fig. 6 is a view partly in plan and partly 30 in section of the ribbon-feeding and vibrating mechanism.

Referring to the drawings annexed by numerals, 10 designates the main frame, on which are mounted in any suitable manner 35 the key-bars 11, each key-bar being provided with a depending ear 12 which is provided with a pin 13 in its lower end, which engages the radial slot 14 in arm 15 journaled on a rock shaft 16 affixed to the lower 40 edges of the side-bars of the frame. Each of the arms 15 is provided with an upstanding arm 17 which is connected by a rear wardly-extending link 18 to the heel of the type-bar 18' of the usual construction. The 45 type-bars are pivotally mounted in the usual manner in the type-bar segment 19. This manner of connecting the key-bars to the type-bars is advantageous in that it enables the type-bar segment to be brought well forward in the machine in order to provide 50 space enough between the type-bar segment and the rear wall of the frame to receive

the platen carriage and connected parts when the machine is compacted, as more fully hereinafter set forth.

55

At each side of the main frame is provided a pair of vertical guide ribs 20 which are engaged by channeled legs 21 of a top plate or frame 22 which carries the usual platen carriage 23. This frame or plate 22 is thus made vertically slidable, and it is held in its adjusted positions in any suitable manner, preferably by spring-actuated latches 24, one of which is mounted in each of the legs 21 and is adapted to engage 60 notches 25 in the guide ribs 20, the engagement of the latches with the notches being preferably a frictional one, so that the movable frame may be raised or lowered by applying a little effort thereto and also in order that, whether the frame be lifted or lowered, it will automatically lock at the desired height. The lower notches 25 are so located that when they are engaged by the latches, the rear portion of the movable 65 frame together with the platen carriage will lie behind the type segment while the mechanism carried by the movable frame will have been lowered to a point approximately 70 on a level with the upper ends of the guides 75 20, thus compacting the machine to the extent of movement of the frame upon the guides.

In connection with the vertically adjustable platen carriage frame, I have provided 80 compactible (preferably telescoping) means for operating the carriage feed, the ribbon feed and the ribbon vibrator. Underneath the key levers, I arrange a universal bar 26 normally pressed up against said levers by 85 means of the springs 27. An escapement lever 28 is connected to this universal bar by means of a link 29, and this escapement controls an escapement wheel 30 affixed to the lower end of the shaft which carries the carriage-feeding pinion 31, said shaft being journaled in a bearing 32^a on the base and consisting of a series of telescoping-sections 32, so arranged that when the supplemental-frame is lowered, these sections telescope 90 into each other sufficiently to permit the frame to be lowered the desired extent, thus avoiding any disconnecting of the carriage-moving parts when the machine 95 100

is compacted. The carriage feed pinion 31 engages a rack 33 mounted on the platen carriage and kept normally in engagement with the pinion by springs 34. This rack bar 33 is permitted a limited sliding movement by means of inclined slots 35, through which pass pins 36, said slots inclining forwardly and toward the left of the machine. Attached to this rack bar is handle 37, by means of which the carriage is manually drawn back to starting position against the action of the usual spring 38. By this arrangement, when the operator grasps the handle 37 and pulls the carriage to the right, this same action will, by reason of the inclined slots 35, cause the rack bar to move rearwardly out of engagement with pinion 31. The pins 36 being rigidly affixed to the carriage and the slots being arranged parallel to each other, the rack bar will be at all times in exact parallelism with the line of travel of the carriage.

The ribbon 39 is carried by two spools 40 whose shafts are mounted on the supplemental frame 22 and are provided each with a ratchet wheel 41. These ratchet wheels are respectively engaged, for rotation of the spool shafts, by pawl 42, each pawl being carried on the forward end of a rod 43 which is normally pulled rearwardly by coil-spring 44 inclosed in cylinder 45, the spring acting against a head 46 affixed to rod 43 and inclosed in the rear end of a cylinder 45. The two cylinders 45 are connected by a bar 47, through which extend the rear ends of rods 43, each of said rods being provided at its rear end with a tappet 48. At a point behind cams 48, rock shaft 49 is journaled in the frame 22, this rock shaft being provided with forwardly-extending fingers 50 which engage said cams when the shaft is rocked to force the pawls forward.

Rock shaft 49 is rocked by suitable connection with the universal bar 26. One arrangement for this purpose is illustrated; this arrangement consists of rearwardly-extending arms 51 affixed to the rock shaft 49 and connected to rearwardly-extending arms 52 carried by the universal bar 26, this connection consisting of an extensible rod composed of linked sections 53, these sections 53 being so connected together that when the supplemental frame 22 is lowered to compact position, these sections slide upon each other to thus shorten the connection between arms 51 and 52. This sliding connection may be obtained in any suitable way; the way I have illustrated this connection is to provide the lower end of each of the upper sections with an eye 54 and have the ends of the adjacent sections extending loosely through said eyes and provided with a stop 55 at their upper ends. It will be observed that when the machine is extended for use, the sections 53 will be in their extended posi-

tion, *i. e.*, with their eyes 54 in contact with the adjacent stops 55, so that upon depression of the universal bar 26 by any one of the key-levers, the rock shaft 47 will be operated, thereby swinging cam-arms 50 upwardly and thus forcing forwardly that one of the pawls 42 which is in operative position with respect to its operating cam 50.

To reverse the ribbon, the pawl frame (47, 45 and 43) is manually shifted laterally to disconnect the pawl which has previously been in operation and to bring the other pawl into operative position with respect to its ratchet wheel and at the same time bring the other cam 48 into alinement with its companion cam 50. To enable this pawl frame to be shifted laterally, the depending eyes 56 which are arranged on the under side of the supplemental frame are laterally enlarged, as shown in Fig. 6.

To vibrate the ribbon, I attach to the shaft 49 a forwardly-extending arm 57 which engages under the vertically-slidable ribbon-guide 58 of the usual construction.

For the sake of compactness, I hold each key-lever 11 normally up by means of a flat spring 59 affixed to the rear part of the base-frame and arranged to press upwardly against the under side of the key-levers. The side wall of the base frame, at points between each pair of guide-ways 20 is cut away to form a large notch or space in the upper edge of the side wall, to thereby permit the platen or the carriage, or both, to project beyond the side walls of the base without in the least interfering with the collapsing of the machine. The case shift in this type of machine may be obtained by either raising and lowering the supplemental frame, or raising and lowering the type-bar segment 105 19; I prefer the latter, and for this purpose the type-bar segment (together with its usual type-bar rest 60 to which it is connected by a suitable bar 61) is mounted to slide vertically on suitable guides 62 on the base. To give the type-segment (which extends upwardly at its end as usual) clearance when the supplemental frame is lowered to collapsed position, said frame is open at its front side, forming forwardly-projecting 110 side arms 63.

The latches 24 are each normally projected by means of a coil-spring 64 and the tension of this spring is regulated by means of screws 65, whereby the desired frictional engagement of the latch with the guide-rib 20 and its notches may be varied from time to time as the springs weaken or the latches wear.

The shifting of the type-bar segment up 125 and down can be accomplished without disturbing the position of the type-bars with reference to the segment or disturbing the key-levers by reason of the link connection 18 between the key-levers and the type-bars. 130

The nature and scope of the invention having been thus indicated and its preferred embodiment having been specifically described, what is claimed as new is:

5. 1. In a typewriter of the class set forth, the combination of a base frame carrying the key-levers, type-bars, a vertically movable supplemental frame supported on said base and carrying the platen carriage, and
10 extensible ribbon-feeding means partly mounted on the base and partly mounted on said supplemental frame, for the purpose set forth.

2. In a typewriter of the class set forth, 15 the combination of a base frame carrying the key-levers, type-bars, a vertically movable supplemental frame supported on said base and carrying the platen carriage, and extensible ribbon-vibrating means partly mounted
20 on the base and partly mounted on said supplemental frame, for the purpose set forth.

3. In a collapsible typewriter, the combination of a base-frame provided at each side with a pair of upstanding guides, a
25 space being left between each pair of guides, and a supplemental frame mounted to slide on said guides and provided with a transversely-slidable platen carriage arranged in alinement with the spaces between the
30 guides, for the purpose set forth.

4. In a collapsible typewriter, the combination with a base-frame, a supplemental frame vertically-slidable on the base-frame and carrying a platen carriage and provided
35 with a pair of forwardly-extending arms, a space being provided in the top-plate of the frame between said arms, a type-bar segment mounted on the base in vertical alinement with the space between said arms, type-
40 bars mounted on said segment and key-levers operatively connected to actuate the type bars.

5. In a collapsible typewriter, a base carrying the type-bars and means for operating them, a supplemental frame adapted to collapse vertically into said base and carrying a platen carriage, and resilient frictional devices for holding the supplemental frame in either its extended position or its
50 collapsed position, means being provided for varying the degree of friction of said holding devices.

6. In a compactible typewriter, the combination of a base frame carrying the key-levers and printing devices, a supplemental frame carrying the platen carriage and mounted on the main frame so as to slide rectilinearly down into the same when the machine is compacted to reduce the vertical
55 dimensions of the machine without increasing its fore and aft dimensions, and exten-

sible ribbon-feeding means partly mounted on the base and partly mounted on said supplemental frame.

7. In a compactible typewriter, the combination of a base frame carrying the key-levers and printing devices, a supplemental frame carrying the platen carriage and mounted on the main frame so as to slide rectilinearly down into the same when the machine is compacted to reduce the vertical dimensions of the machine without increasing its fore and aft dimensions, and extensible ribbon-vibrating means partly mounted on the supplemental base and partly mounted
65 on said supplemental frame.

8. In a compactible typewriter, the combination of a base frame carrying a type segment and printing instrumentalities, a supplemental frame mounted on the base frame
70 so as to drop down behind said segment, said supplemental frame carrying a platen carriage and being provided also with a pair of arms projecting forwardly at either side of the segment, a ribbon-spool journaled on the
75 forward end of each of these arms, and a ribbon-vibrating and feeding mechanism mounted partly on said supplemental frame and partly on the base frame.

9. In a collapsible typewriting machine, 90 the combination of a base frame part, a type segment mounted on the base frame part, type bars pivotally mounted on said segment, key levers mounted on the base frame part and operatively connected to actuate
95 the type bars, a universal bar mounted on the base frame part, a supplemental frame part slidably connected to the base frame part to move downwardly relatively thereto to reduce the height of the machine, a
100 platen carriage supported on the supplemental frame to move therewith from a normal position above and at the rear of the type segment to a lower position at the rear of the segment when the machine is collapsed, said supplemental frame having forwardly extending rigid portions at opposite sides thereof movable downwardly at the ends of the type segment when the machine
105 is collapsed, ribbon spools mounted on said forwardly extending portions of the supplemental frame, collapsible carriage feeding mechanism mounted partly on each of said frame parts, and collapsible ribbon feeding mechanism mounted partly on each of said frame parts, said carriage feeding mechanism and ribbon feeding mechanism being
110 operatively connected with the universal bar.

This specification signed this second day 120
of July A. D. 1917.

STANLEY R. DE PUE.
